US0D1045019S

(12) **United States Design Patent** (10) Patent No.: **US D1,045,019 S**
(45) Date of Patent: ** Oct. 1, 2024

(54) **AIR RELEASE VALVE**

(71) Applicants: **Qianqian Wang**, Zhejiang (CN);
Xianming Qiu, Zhejiang (CN)

(72) Inventors: **Qianqian Wang**, Zhejiang (CN);
Xianming Qiu, Zhejiang (CN)

(**) Term: **15 Years**

(21) Appl. No.: **29/946,335**

(22) Filed: **Jun. 7, 2024**

(51) LOC (14) Cl. **23-01**

(52) U.S. Cl.

USPC **D23/233**

(58) **Field of Classification Search**

USPC D23/233, 235, 248, 249

CPC F16K 24/00; F16K 17/00

See application file for complete search history.

(57) **CLAIM**

The ornamental design for an air release valve, as shown and described.

DESCRIPTION

FIG. 1 is a perspective view of an air release valve showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof; and,

FIG. 9 is an enlarged view of area 9 in FIG. 1.

The broken lines in the drawings are for the purpose of illustrating portions of the air release valve and form no part of the claimed design. The dot-dash broken lines in the drawings indicates cutoff boundaries for the enlarged detailed portion views and form no part of the claimed design.

1 Claim, 9 Drawing Sheets
